UNITED STATES PATENT OFFICE.

HUGO SCHNEIDER, OF CLEVELAND, OHIO.

COMBINED PUMP AND MEASURE.

SPECIFICATION forming part of Letters Patent No. 624,550, dated May 9, 1899.

Application filed April 22, 1898. Serial No. 678,461. (No model.)

To all whom it may concern:

Be it known that I, HUGO SCHNEIDER, a citizen of the United States, residing at Cleveland, in the county of Cuyahoga and State of Ohio, have invented certain new and useful Improvements in a Combined Pump and Measure; and I do declare that the following is a full, clear, and exact description of the invention, which will enable others skilled in the art to which it appertains to make and use the same.

My invention relates to a combined pump and measure; and the object of the invention is to provide means for pumping liquids and the like from vessels and at the same time measuring and recording the amount as it is pumped, substantially as shown and described, and more particularly pointed out in the claims.

Figure 1 is a side elevation of my improved pump and measure within a barrel and as in use. Fig. 2 is a sectional view enlarged from Fig. 1, but broken into sections. Fig. 3 is a side view of the outer end of the spout with the valve therein. Fig. 4 is a perspective view of the three separate parts of the piston and valve.

In the accompanying drawings, A represents the pump proper, consisting of the shell or walls 2, open at both ends. The lower end has a cap 3, and this cap contains a valve 4, having a head and central stem 5, with a guide 6 screwed thereon. The valve-head is kept upon its seat 7 by a light spring 8, interposed between the seat and the guide 6. Lugs 9 project downward from cap 3 to raise the valve a sufficient distance above the bottom of the vessel and afford a free working thereof, and they also provide a free and open passage for the discharge of the liquid. The piston B is designed to work back and forth within the casing 2, and this piston is constructed in three parts, as more clearly shown in Fig. 4. The upper part 10 has a central boss 11, with an opening 12 therein, and this boss is supported on part 10 by radiating arms 13, thus giving a free and open space between part 10 and boss 11 for the passage of the liquid. The lower part 14 of the piston is threaded into part 10 and is made open at the bottom, with a seat 15 for the valve 16. The valve 16 has guide-lugs 17, and a central

stem 18 projects upward into the opening 12. A spring 19 encircles this stem and bears against the bottom of the boss 11 and assists in keeping the valve 16 closed when in one of the operating positions.

Now in order that the pump A may be supported I employ a tube 20, screwed into the top of the casing A, and an adjustable flanged collar 22 is free to slide over this tube, and a bolt 23 fastens this collar at any height, according to the height of the barrel or vessel that the tube is within. As here shown, the flange of the collar 22 has screw-holes, and it is by this means that it is tacked or screwed on the head of the barrel, thus providing a rigid support for the whole structure.

The body C of the spout 24 is screwed on and supported at the top of the tube 20, and a valve 25 is seated within the outer end of the spout 24. The stem 26 of this valve is supported by the nut and bushing 27, screwed into the top of the outer spout-chamber 28. Screw 29 on stem 26 rides within the inclined slot 30 in nut 27, and when the handle 31 is turned the valve is raised from its seat. The reverse motion will close the valve. This valve is located at the extreme outer and lower end of the spout and is designed to prevent the loss of liquids that remain in the end of the spout after each withdrawal. Cleanliness is thereby obtained, and where liquids, such as molasses or the like, are used flies and insects are kept out of the end of the spout, and when the next withdrawal occurs there is no danger of any foreign or unclean matter being discharged with the liquid.

In order to operate the pump-piston B, I provide the body C with a recessed extension or housing 33, within which a short rocker-arm 34, mounted on the cross-shaft 35, is free to operate. The end of this arm 34 is pivoted to a piston-rod 36, which passes down through tube 20 to the piston B. The lower end of the piston-rod and the piston B is provided with a ball or swiveled joint 37 and nut 38, and this construction allows the slight lateral play of the rod when the arm 34 is operated. To operate this arm, I attach a lever 39 to the end of the shaft 35 outside of the body C, and a certain fixed and adjusted movement of this lever 39 serves to operate the piston B to pump a certain amount of liquid at each full stroke.

To determine this amount and to adjust the stroke, a beveled arm 40 is adjustably mounted on the top end of the lever, and the beveled edge of this arm comes in contact with a lug 41 on the body C, thus limiting the movement of the lever in this direction. The lower end of the lever comes into contact with a projection 42 when thrown in the opposite direction. The movement of this lever is also utilized to register the amount of liquid pumped, and to this end a dial 43 is rotatably mounted on the side of the body C, and a spring-pressed finger 44, pivotally supported on the extremity of the lever, engages the ratchet-teeth on the edge of the dial when the said finger is brought forward. A finger 45, supported on lug 41, indicates the movement of the dial, and figures on the face thereof show the amount of liquid pumped.

From the dotted position of the lever shown in Fig. 1 it will be seen that the lever must practically travel its full distance before the finger 44 engages the dial and records the amount of liquid pumped, and this is so intended to prevent the giving of a short measure.

As seen in the drawings, the pump A is at the extreme bottom, where the entire contents of the vessel can be emptied. When in use, the pump A, tube 20, and spout 24 are always filled to the valve 25 in the spout, and when the operator depresses the handle 39 there is an immediate flow. The amount of this flow is determined by the length of the stroke of the piston B. When the piston rises, the valve 16 closes and forces the liquid up and through valve 25, which has previously been opened. The lower valve 4 opens as the piston B rises, and the liquid is drawn into the chamber of pump A. When the piston descends, the pressure closes valve 4, and the liquid in the chamber forces valve 16 open, thus allowing it to pass and fill tube 20, and thereby keeping the tube and pump full at all times. The amount of liquid to be pumped at each stroke can be exactly determined by setting the beveled arm 40, and a certain number of strokes will discharge a given quantity of liquid. Thus four strokes will discharge a pint, eight strokes a quart, and so on. This measurement is accurate and is accomplished by and is due to my construction. By placing the pump at the bottom of the vessel the entire contents can be emptied, and the tube above the piston always contains the same amount of liquid, so that when operated the quantity discharged is determined by the stroke of the piston. This stroke can be

lengthened or shortened by the arm 40, as heretofore described. 60

By reason of confining the short arm 34 and its connecting-rod entirely within the body C and tube 20 and mounting the arm 34 on a cross-shaft 35, which has but a slight rotative movement when said parts are operated, I avoid and overcome all leakage. The connecting-rod 36 could be made to project through the top of the body C and be operated from the outside by a handle, lever, or otherwise; but this construction is not deemed as practical as that herein shown owing to the fact that when heavy and thick liquids are pumped leakage is sure to occur, the liquid forcing itself to the outside by the reciprocation of the rod. Then the liquid gums and hardens, and after a time, especially in winter, it is nearly impossible to operate the pump. Where all the reciprocating parts are placed entirely within the body, more free action is obtained and leakage, with its objectionable features, is entirely eliminated. 70 80

The valves, spout, pump-casing, and pump mechanism are all tinned to prevent corrosion.

What I claim is— 85

1. In a combined pump and measure, a tube, pump mechanism at the lower end of said tube, a spout and body at the top of said tube, a valve at the lower and outer end of said spout, a connecting-rod and arm within said tube and body, a lever on the outside to operate said rod and arm, an adjustable beveled arm on the lever and lugs on the body to limit the movement of said lever, a rotating dial and indicator on said body to record the amount of liquid pumped, and means on said lever to operate said dial at the end of each stroke, substantially as described. 90 95

2. In a pump and measure, a tube having a spout-body at the top and a pump-casing at the bottom thereof, a valve in said spout and pump mechanism in said casing, a connecting-rod swiveled to said mechanism, and pivoted to an arm 34 within the spout-body, a lever 39 to operate said arm, a beveled adjustable arm on said lever and lugs on said body to limit the movement of said lever, and a dial on said body operated by means of said lever to record the amount of liquid pumped, substantially as described. 100 105 110

Witness my hand to the foregoing specification this 12th day of April, 1898.

HUGO SCHNEIDER.
